UNITED STATES PATENT OFFICE.

ANTON E. HAGBLOM AND ROLAND W. CHRISTENSEN, OF CHICAGO, ILLINOIS.

KEY GUARD.

Application filed February 15, 1922. Serial No. 536,690.

To all whom it may concern:

Be it known that we, ANTON E. HAGBLOM, a citizen of Finland, and ROLAND W. CHRISTENSEN, a citizen of the United States, residing at Chicago, in the county of Cook and State of Illinois, have invented a new and useful Improvement in Key Guards, of which the following is a specification.

Our invention relates to an improvement 10 in the type of key-guard which is adapted to be affixed for use on the inner face of a door, to so engage the key in the lock as to prevent it from being dislodged through the key-hole from outside in any attempt to 15 unlock the door from without. Referring to the accompanying drawing—

Figure 1 is a broken face-view of a door showing our improved key-guard in operative position thereon; Figure 2 is an enlarged perspective view of the key-guard, and Figure 3 is a broken view of the same in elevation, showing the pivotal spring-pressed connection of one with the other of the two members of which the device is 25 composed.

Our key-guard comprises a lower member 4 and an upper pivotal spring-pressed latch-member 7, both members being preferably stamped out of sheet-metal. The member 4 is formed with an offset head 5, through openings in which the guard may be secured to the inner face of the door below the escutcheon 6 thereon to extend upwardly along and close to the face of the latter with the key-latch end of the member 7 normally registering with the key-hole. On the member 4 is formed a hook 4^a for accessibly hanging a door-key when out of use. The members 4 and 7 are pivotally connected, the latter to the former, at their mutually overlapping end-portions, a guide-tongue 7^a projecting from the lower extremity of the member 7 through a curved slot 4^b in the upper portion of the headed member; and a spring 4^c, applied to the pivot, connects the tongue with a lip 4^d projecting from the upper extremity of the member 4. The upper portion of the member 7 is offset, as shown in Fig. 2, from the lower portion to cause it to be close to the face of the escutcheon 6 when the guard is secured in place on a door, to operate

as hereinafter explained. A semicircular recess 7^b is formed in an edge of the member 7 near its upper end to engage the cylindrical shank of a key 8, and from this recess extends a slot 7^c to receive edgewise a flat key when used to lock a door provided with our improved device.

To apply our improved key-guard it is 60 fastened, as by the screws shown in Fig. 1, through the head 5 to a door 9 centrally below the lower end of the escutcheon to extend upwardly along the face of the latter and bring the recess 7^b into position to 65 surround the shank of a key 8 when in the key-hole. The spring 4^c normally retains the pivotal latch-member in that position to obstruct dislodgment of the key, whether of the type shown or of the other type referred to. To permit insertion or withdrawal of the key, the member 7 is turned on its pivot to remove the recessed end thereof from obstructing at the key-hole. To facilitate that purpose a thumb-piece 10 75 is formed to project as shown from the pivotal member. Upon releasing the thumb-piece, the spring 4^c returns the member 7 to its normal obstructing position.

We realize that considerable variation is 80 possible in the details of the construction herein shown and we do not intend to limit our invention thereto except as pointed out in the following claims, in which it is the intention to claim all the novelty there may 85 be in the invention as broadly as permissible by the state of the art.

What we claim is:

1. A key-guard comprising a member having a head through which to secure it in place on the inner face of a door beyond the key escutcheon thereon and provided with a slot, and a member overlapping at one end-portion the adjacent end-portion of the headed member and having a pivotal 95 spring-pressed connection with the latter to extend the pivotal member normally adjacent the key-hole where it is provided with means for engaging a key therein, said pivotal member having a tongue projecting 100 through the slot in the headed member.

2. In combination with a door having a key-hole-containing escutcheon on its inner face, a key-guard comprising a member hav-

2

ing an offset head through which it is secured to the door below the escutcheon to extend upwardly along the latter, and a member overlapping at one end-portion the adjacent end-portion of the headed member and having a pivotal spring-pressed connection with the latter to extend the pivotal

member upwardly along the escutcheon adjacent the key-hole where it is provided with means for engaging a key therein, said pivotal member having relatively offset upper and lower portions.

ANTON E. HAGBLOM.
ROLAND W. CHRISTENSEN.
